(57) **CLAIM**

The ornamental design for a foldable slumber bed, as shown and described.

DESCRIPTION

FIG. 1 is a front perspective view of a foldable slumber bed in accordance with a preferred embodiment of my new design; FIG. 2 is a top plan view thereof;

FIG. 3 is a bottom plan view thereof;

FIG. 4 is a right side elevation view thereof, a left side elevation view thereof being a mirror image;

FIG. 5 is a front elevation view thereof; and,

FIG. 6 is a rear elevation view thereof.

The broken lines in the figures are for the purpose of showing environmental structure and form no part of the claimed design.
